J. J. REKAR.

AERIAL MACHINE.

APPLICATION FILED AUG. 19, 1908.

922,952.

Patented May 25, 1909.

UNITED STATES PATENT OFFICE.

JOHN J. REKAR, OF SAN FRANCISCO, CALIFORNIA.

AERIAL MACHINE.

No. 922,952.

Specification of Letters Patent.

Patented May 25, 1909.

Application filed August 19, 1908. Serial No. 449,253.

To all whom it may concern:

Be it known that I, JOHN J. REKAR, citizen of the United States, residing in the city and county of San Francisco and State of California, have invented new and useful Improvements in Aerial Machines, of which the following is a specification.

My invention relates to an aerial apparatus.

10 It consists in the combination of parts, and in details of construction which will be more fully explained by reference to the accompanying drawings, in which—

Figure 1 is a side elevation. Fig. 2 is a top view. Fig. 3 is a front view partially in section. Fig. 4 is a section showing the internal structure and bracing of the gas-holder. Fig. 5 shows the channeled construction of the holder.

20 The gas-holder A of my apparatus, which is elongated horizontally, may be made with an exterior skin of any suitable or well known material of sufficient lightness and ability to retain gas for a long period. In order to 25 retain it in shape, I have shown a series of truss frames 2, which maintain the outer skin in proper distention, these trusses being spaced lengthwise; the front and rear of the gas-holder are preferably made wedge-shaped, as shown at 3, converging from the 30 body A to a vertical edge at front and rear. By this construction I reduce the air resistance, and provide a vertical edge to which the rudder 4 may be hinged or connected as 35 shown. Upon the sides of this structure are hinged aeroplanes 5 which project preferably from points somewhat above the central line of the gas-holder. These aeroplanes 40 may also be connected with other aeroplanes 6 hinged lower down upon the exterior of the gas-holder, and by suitable connections with the engine-room, they may be raised or depressed as desired. In the present case I 45 have shown the aeroplanes 5 as being slightly arched in transverse section, and they may have upwardly projecting extensions or wings 5^a.

Upon the top of the apparatus are vertical cylindrical shells 7, and within these propellers are mounted to revolve on vertical shafts. 50 Connections are made between each shell 7 and the space below the aeroplanes 5, by means of open chutes or channels 8, so that when the propeller is revolving in the right 55 and proper direction, air will be drawn in from the upper part of the shell, and will be

forced out under the aeroplanes; or when the two sets 5 and 6 are employed, it will be ejected between them. This assists in raising the apparatus from the ground when 60 it is made slightly heavier than the buoyant power of the contained gas, and by moving the aeroplanes as the air passes out between them, I am enabled to assist in the operation of the apparatus.

65 The engine-room or car 9 is suspended beneath the gas-holder, and may contain engines from which power is derived for operating the apparatus.

I have here shown propellers 10 fixed upon 70 shafts 11 which are journaled along the upper and lower edges of the vertical wedge-shaped portion of the apparatus, and from which connections extend to a point in the engine-room where power may be applied to rotate 75 them. The vertical shaft of the horizontal rotating propeller or propellers may be driven in like manner from the engine.

I prefer to mount the apparatus upon light 80 wheels 12 so disposed that it can run lightly upon the ground until sufficient speed has been attained so that, with the lifting effect of the propeller and the aeroplanes, together with the buoyant gas, the device may rise in the air, after which it may be controlled by 85 the operation of the rudders; the vertical rudder 4 serving to steer it from side to side.

It will be understood that the car may be 90 of any suitable or desirable shape. I prefer to make it with its under body of a boat or similar shape so that the apparatus may be started upon water, and when sufficient speed has been attained, it may rise, and thereafter be manipulated in the air. Such a form also allows it to descend upon the water and injurious shocks are prevented. If by accident, or for other reason the machine should 95 descend when passing over a body of water, the boat shaped car would support it, and the propellers could be used to drive the machine without raising it from the surface.

In Fig. 5 I have shown a convenient method for applying the truss frames 2 in which the outer covering of the gas-holder is contracted or drawn into a smaller diameter 105 at each of these trusses, than the main diameter, as at a, and the trusses fit into these grooves or channels and form exterior braces and supports against undue extension. At each of these sections, the gas-holder may be 110 tied, or otherwise be detachably connected with the trusses.

The rudder 4 has suitable cords or connections extending back to the engine-room, and connected means by which the steering may be controlled.

5 4^a is a horizontally hinged rudder so disposed with relation to the rudder 4 that it may be moved up or down independently of the latter, and thus serve in conjunction with the aeroplanes, to raise or depress the 10 apparatus when in motion. The vertical rudder may be extended above and below the upper and lower horizontal lines of the gas-holder, and will thus expose more surface, and insure a more perfect control.

15 15 By means of a weight 15 suspended below the car, and cords 16 by which said weight may be moved forward or backward I am enabled to tilt the apparatus to assist in raising or depressing it, in conjunction with the propelling and steering mechanism.

Having thus described my invention, what I claim and desire to secure by Letters Patent is—

1. The combination in an apparatus of the 25 character described, of a gas-holder, a vertically disposed shell, a propeller revolvable upon vertical axis within said shell, passages leading downwardly and transversely outward from the shell, and aeroplanes adjustably connected with the sides of the apparatus above and below the air exit passages.

2. In an apparatus of the character described, a substantially cylindrical gas-holder having transverse truss frames by 35 which the shape of the body is maintained, the front and rear ends of said holder converging to vertically disposed ends, a rudder hinged to one of said vertical ends and a horizontally disposed rudder hinged and 40 movable with relation to the first named rudder, and propellers located at the vertical ends.

3. In an apparatus of the character described, a gas-holder having a substantially 45 cylindrical central section and ends converging to vertical edges, with rudders hinged to one end, and propellers at either end, vertical shells on the upper part of the gas-holder, passages leading downwardly and outwardly

from said shells through the sides of the gas- 50 holder, propellers mounted to revolve in said shells, aeroplanes hinged above and below said passages, those upon each side being connected to move in unison, and a structure suspended beneath the gas-holder, and 55 adapted to contain a motor and operating connections.

4. In an aerial apparatus of the character described, a gas-holder having circumferential channels at intervals of less diameter 60 than the main diameter, truss frames fitting said channels, and means for raising, propelling and steering said apparatus.

5. In an aerial apparatus of the character described, a horizontally disposed tubular 65 gas-holder having its ends convergent in vertical planes to narrow vertical terminating edges, circumferential grooves or channels formed in said shell at intervals between the convergent sections, trusses removably 70 fitted in said grooves, and co-acting elevating, propelling, and steering mechanism.

6. The combination in an aerial apparatus of the character described, of a horizontally disposed tubular gas-holder with vertical 75 wedge-shaped ends and circumferential detachable trusses, a boat-shaped car and movable counter-weight, elevating, propelling, and steering mechanism, adjustable aeroplanes in pairs upon the sides of the gas- 80 holder, and passages diverging from the elevating devices, and discharging below the upper pairs of aeroplanes.

7. In an aerial apparatus of the character described, a horizontally disposed tubular 85 gas-holder, with detachable interspaced truss frames, and vertical wedge-shaped ends, and raising, propelling, and steering mechanism, said steering mechanism including horizontal and vertical rudders, turnable upon the 90 vertical end of the gas-holder.

In testimony whereof I have hereunto set my hand in presence of two subscribing witnesses.

JOHN J. REKAR.
